TENSION DEVICE FOR LOOM SHUTTLES

Isaac Snow, Lawrence, Mass., assignor to Draper Corporation, Hopedale, Mass., a corporation of Maine.

Application January 22, 1935, Serial No. 2,934

5 Claims. (Cl. 139—223)

The present invention pertains to automatically threading loom shuttles and has more particular reference to tension devices in such shuttles for tensioning the running filling.

5 Shuttles of the type mentioned have been provided with spring clamp tension devices wherein tension on the running filling is produced by opposed friction plates which are yieldingly pressed together by coiled springs and the like. Such devices have proven unsatisfactory in that they are comprised in part of small, delicate springs, guide pins and the like which are expensive to manufacture and which are inherently incapable of giving good service in a loom shuttle.

10 I propose to provide an automatically threading loom shuttle with a spring clamp tension device which shall be simple and inexpensive to manufacture and which shall be stronger and more durable than the prior devices of like nature. 15 This desirable result is accomplished by means of a spring arm fixed to the threading block of the shuttle and carrying a friction surface which cooperates with a surface on the lower side of an outwardly and rearwardly extending thread 20 guard. Such a construction may be devoid of the small, delicate parts found so disadvantageous in prior constructions.

25 A further object of the invention is to provide a spring clamp tension device which possesses the desirable features above mentioned and which, in addition, shall be operative to tension the filling only during the first pick after transfer.

30 The preferred embodiment of the invention is illustrated on the accompanying drawing, of which:

35 Fig. 1 is a perspective view of the delivery end of a shuttle comprising the said preferred embodiment;

40 Fig. 2 is an elevational view of the outer end of the threading block detached from the shuttle;

45 Fig. 3 is a rear elevational view of the same; and

Fig. 4 is a plan view of the shuttle of Fig. 1 50 showing the position of the filling during the first pick after transfer.

The shuttle shown on the drawing is comprised of the usual body 1 having means (not shown) for detachably holding the bobbin 2 55 which is adapted to be automatically ejected upon depletion of the filling supply and replaced by a fresh bobbin.

The shuttle is provided with a threading block 55 having a front wall 3 and a rear wall 4 defining a thread passage 5 which extends longitudinally

of the shuttle. A thread guard 6 extends from the front wall 3 outwardly and rearwardly over the thread passage adjacent the outer end thereof. The expressions "front", "rear", "outwardly" and the like, are to be applied considering the shuttle to be positioned in a loom in the usual manner.

When a fresh bobbin is first transferred to the shuttle the filling end *f* extends outwardly therefrom directly over the thread passage. When the shuttle is first started on the first pick after transfer the filling swirls rearwardly and downwardly about a retaining hook 7, and also rearwardly and downwardly about the rearward, free end of the thread guard 6, so as to enter the thread passage 5. Thereafter, during such first pick after transfer, the filling extends from the bobbin through the thread passage and longitudinally outwardly of the shuttle beneath the thread guard. During the second pick after transfer the filling passes down into a side delivery eye 8 as shown on Fig. 1.

The specific embodiment of the novel form of spring clamp tension, as shown on the drawing, is comprised of but two essential parts. One of these parts is the thread guard 6. The lower surface of the thread guard may be flattened adjacent the rearward, free end thereof, to provide a friction surface. This surface is intersected by the path which the running filling assumes during the first pick after transfer. The other part is comprised of a spring arm 9, preferably of spring steel. This arm is carried by the rear wall of the threading block, and to this end may have its inner end fixed in such wall. The arm extends longitudinally outwardly and thence forwardly from its inner, fixed end, and is biased into yielding engagement with the aforementioned friction surface on the thread guard.

The free end of the arm 9, where it cooperates with the thread guard, is provided with a friction surface, preferably by enlarging the arm itself to form a friction plate 10 as shown. Both the plate and friction surface are in horizontal planes, thereby providing a spring clamp tension which opens rearwardly to receive the running filling as the latter swirls about the thread guard during the first pick after transfer. If desired, the tension may be adjusted by a screw 11 which is threaded into the rear wall 4 and bears upwardly against the arm 9 intermediate the ends of the latter.

The tension device described is well adapted to providing for tensioning the filling during only the first pick after transfer, and releasing the

filling as it passes down into the side eye. To this end, it opens forwardly, and communicates with the side eye through the usual space between the thread guard and the shuttle body. 5 It will be noted that the filling, when fully threaded, extends through the thread passage 5, thence downwardly and forwardly between guards 12 and 13, and thence out the side eye. It will also be noted that the path of the fully 10 threaded filling is spaced away from the tension device.

The invention as thus disclosed provides a tension device which is simple, extremely sturdy, and particularly efficient in operation. In addition to its functions as a tension device, the specific construction disclosed serves to prevent the filling from becoming unthreaded by throwing out of the thread passage when the shuttle boxes on its eye end. 15

Having fully disclosed the preferred embodiment of the invention, I claim:

1. An automatically threading loom shuttle having a side delivery eye, a threading block comprising front and rear walls defining a longitudinally extending thread passage and a thread guard extending from said front wall outwardly and rearwardly over said thread passage at the outer end thereof, and a first pick tension device comprised of a spring arm carried by said rear wall and extending outwardly and forwardly therefrom into yielding engagement with the lower surface of said thread guard. 25

2. An automatically threading loom shuttle having a side delivery eye, a threading block comprising front and rear walls defining a longitudinally extending thread passage and a thread guard extending from said front wall outwardly and rearwardly over said thread passage at the outer end thereof, the rearward end of said 30 thread guard being free and having a friction surface on the lower side thereof, and a spring arm having its inner end fixed to said rear wall and its outer end free and yieldingly engaging said friction surface, said arm and surface comprising a spring clamp tension device engaging and tensioning the filling when the latter extends through said thread passage and longitudinally outwardly of the shuttle beneath said 35 thread guard.

3. An automatically threading loom shuttle having a side delivery eye, a threading block

comprising front and rear walls defining a longitudinally extending thread passage and a thread guard extending from said front wall outwardly and rearwardly over said thread passage at the outer end thereof, and a first pick tension device comprised of a friction surface on the lower side of said thread guard adjacent the outer end thereof and a spring arm having its inner end fixed to said rear wall and its outer end formed to constitute a friction plate cooperating with said friction surface, said shuttle also having a tension adjusting screw carried by said rear wall and bearing against said arm intermediate the ends of the latter. 10

4. An automatically threading loom shuttle having a side delivery eye, a threading block comprising front and rear walls defining a longitudinally extending thread passage and a thread guard extending from said front wall outwardly and rearwardly over said thread passage 15 at the outer end thereof, and a spring clamp tension device for engaging and tensioning the running filling only during the first pick after transfer, said tension device being comprised of a friction surface on the lower side of said thread 20 guard adjacent the rearward end of the latter and a spring arm having its inner end fixed to said rear wall and its outer end formed into a friction plate cooperating with said friction surface, the said plate being spaced away from the path which the running filling occupies when 25 it is fully threaded into said delivery eye. 30

5. An automatically threading loom shuttle having a side delivery eye, a threading block comprising front and rear walls defining a longitudinally extending thread passage and a thread guard extending from said front wall outwardly and rearwardly over said thread passage at the outer end thereof, the rearward end of said 35 thread guard being free and having a horizontal friction surface on the lower side thereof, and a spring arm having its inner end fixed to said rear wall and its outer end formed into a horizontal friction plate biased by said arm into engagement with said friction surface, said surface and plate constituting a spring clamp tension 40 device which is open rearwardly to receive the running filling during the first pick after transfer and which is open forwardly toward said side 45 delivery eye.

ISAAC SNOW.
